WALL HYDRANT

Joseph C. Woodford, Spring Lake, Mich., assignor to
Woodford Manufacturing Company, Des Moines, Iowa,
a corporation of Iowa

Filed Aug. 21, 1968, Ser. No. 13,228

Term of patent 14 years

Int. Cl. D23—01

U.S. Cl. D23—12

FIG.1

FIG.5

FIG.3

FIG.2

FIG.4

FIG.6

FIG. 10

FIG. 8

FIG. 7

FIG. 9

FIG. 11

FIGURE 1 is a perspective view of a wall hydrant showing my new design;

FIGURE 2 is a front elevational view thereof;

FIGURE 3 is a left side elevational view thereof;

FIGURE 4 is a right side elevational view thereof;

FIGURE 5 is a top plan view thereof;

FIGURE 6 is a bottom plan view thereof;

FIGURE 7 is a front elevational view of a modified form of the wall hydrant shown in FIGURE 1;

FIGURE 8 is a left side elevational view of FIGURE 7;

FIGURE 9 is a right side elevational view of FIGURE 7;

FIGURE 10 is a top plan view of FIGURE 7; and

FIGURE 11 is a bottom plan view of FIGURE 7.

I claim:

The ornamental design for a wall hydrant, as shown and described.
